BERNHARD GUSTAFSON, DECEASED, LATE OF PLAINFIELD, NEW JERSEY, BY KATHERINE NEILSON COLTON, (FORMERLY KATHERINE NEILSON GUSTAFSON,) EXECUTRIX, OF PLAINFIELD, NEW JERSEY, ASSIGNOR TO CROSS PAPER FEEDER COMPANY, OF PORTLAND, MAINE, A CORPORATION OF MAINE.

SHEET-FEEDING MECHANISM.

1,174,314.

Specification of Letters Patent.

Patented Mar. 7, 1916.

Substitute for application Serial No. 856,545, filed August 13, 1914. Original application filed July 29, 1908, Serial No. 445,853. Divided and this application filed December 3, 1914. Serial No. 875,259.

To all whom it may concern:

Be it known that BERNHARD GUSTAFSON, deceased, late a citizen of the United States, and a resident of Plainfield, in the county of 5 Union and State of New Jersey, did invent certain new and useful Improvements in Sheet-Feeding Mechanism, of which the following is a specification.

The invention relates to sheet feeding machines, and more particularly to retarding mechanism for such machines.

This application is a division of application Serial No. 445,853, filed July 29, 1908.

Machines of the class to which this invention is applicable usually comprise a support for the pile or bank of sheets, sheet segregating devices in the form of one or more combing wheels, and delivery devices in the form of gripping rolls by which the sheets are seized and taken from the pile or bank. The top sheet is advanced into position to be seized by the gripping rolls by one or more combing wheels working in conjunction with trip levers that are actuated by 15 the sheet as it is combed to the point of delivery. While the top sheet is being removed by the gripping rolls, a retaining device is brought down into contact with the next succeeding sheet at the rear of the pile 20 to keep the same in place during the removal of the top sheet. A retarding device or tail drag is sometimes used for bearing on the top of the pile at the rear of the combing wheels to retard the advance of the sheets 25 by the combing wheels, and it is with such a retarding device, and the means for operating or controlling it, that the present invention is concerned. Retarding devices or tail drags as heretofore constructed apply a 30 constant pressure during the combing intervals to the sheets back of the combers, and tend to equalize the pressure between the sheets and to render the separation more uniform. While these retarding devices 35 tend to equalize the separation between the individual sheets in the pile or bank, they also tend to hold back or retard the forward movement of the sheets during the action of the combers, and to thus increase the separa-

tion and increase the period during which 50 the combers must remain in action in order to advance the top sheets into position to be taken away by the delivery devices. This separation between successive sheets is therefore liable to become so great that the top 55 sheet will not be advanced by the combers into position to be seized and carried away by the delivery devices within the interval during which the combers can remain in action, (i. e., within the combing interval). 60

It is accordingly the object of the invention to provide novel and improved retarding mechanism which will act to automatically equalize the period during which the combers must remain in action in order to 65 advance the top sheet into position to be taken away by the delivery devices. To this end the invention contemplates the provision in a machine provided with a combing device for acting on the sheets, of a retarder or tail drag the retarding action of which is automatically varied to equalize the period of activity of the combing device. Since the pressure of the retarder on the sheets, if maintained, may unduly increase the separation and the length of comb (i. e., the period of activity of the combing device required to bring the sheet into position), the mechanism which actuates or controls the retarder is constructed to relieve the pressure on the sheets during the combing interval. In the preferred construction the relieving of the pressure is controlled by the movement of the sheets through the trip devices which cause the comb to be thrown 70 out of action, although this is not essential to the broader scope of the invention. In the preferred construction, the application or increase of pressure by the retarder is 75 also controlled by the movement of the sheets, and since the retarder should apply pressure to increase the separation, and the length of the comb when the separations become slight, or the comb abnormally short, the mechanism for controlling or actuating 80 the retarder is constructed to press the retarder on the sheets when the comb falls below a predetermined length. 85

The features of the invention outlined above, as well as further features set forth in the claims, will be readily understood from an inspection of the accompanying drawings and the following detailed description of the mechanism illustrated therein.

In the drawings, Figure 1 is a side elevation illustrating an embodiment of the invention, parts being broken away and others shown in section; Fig. 2 is a broken side view, showing the operative parts of the aforesaid retarding device in retracted position; Fig. 3 is a view similar to the preceding, but with the retarding device and operative parts thereof down in position to exert pressure upon the paper pile; and Figs. 4 and 5 are details of some of the operative parts in changed positions.

Similar parts are designated by corresponding reference characters throughout the several views.

The machine to which the improved sheet retarding mechanism is herein shown applied for use is a sheet feeding machine of that class or type which is provided with means for supporting a pile of sheets as indicated at 11 in Figs. 1, 2 and 3 of the drawings, in such position that their forward edges, when advanced, are adapted to be moved along or across a throat or plate 12, in position to be individually seized and withdrawn by means of a pair of suitably actuated grip rollers 14 and 15, or equivalent sheet taking means, which operates in a well known way to deliver the sheets singly and successively to a printing, folding or other machine in connection with which the sheet feeder is employed.

A comber or segregating device 21, which as herein shown is made in the form of a combing wheel, continuously driven in a well known way, is employed to separate the sheets from the stack or pile and to advance them along or across the throat or plate 12 into position to be seized and withdrawn from said stack or pile by the operation of the grip rollers or equivalent sheet taking means, and as herein shown an arm or lever 22 is employed for supporting and moving the comber 21 into and out of operative or feeding engagement with the sheets, being capable of downward movement to lower said comber so that it may rest upon and in feeding engagement with the topmost or endmost sheet of the bank or pile, in order that said sheet may be fed forwardly or advanced into position to be seized and withdrawn by the operation of said grip rollers 14 and 15.

When the sheet shall have been properly advanced ready to be seized by said grip rollers, said arm or lever 22 serves as a means for elevating said comber in order that it may be lifted out of contact with

the topmost sheet of the stack or pile during the operation of said grip rollers, it being understood that, as the topmost sheet is moved or fed forward during the rotation of said comber, the friction of each sheet upon that next beneath it in the pile or stack operates to communicate the forward or combing movement in a gradually lessened degree to the several sheets at the top of the pile next beneath the topmost sheet in such manner that their forward edge portions are gradually and progressively advanced or combed forward over the feed plate 12, as hereinbefore described and as indicated in the drawings.

The downward movement of the arm or lever 22, which serves to lower the comber into feeding contact with the sheets, as in other machines of this class or type, may be accomplished under control of a cam or equivalent means secured to the cam shaft 105 and arranged to engage an arm projecting downward from the arm 22. Since there is a certain irregularity in the feeding action arising out of contact of the comber upon the sheets, rendering it necessary to vary the time during which the comber rests in lowered position and feeding contact upon different or successive sheets, or in other words, to lift the comber at different times from different sheets, accordingly as each sheet may have been combed forward or advanced to a greater or less degree, the arm or lever 22 by means of which the comber is raised from the sheets, will ordinarily be provided with spring-actuated lifting means, normally held inoperative by a latch or detent which in itself is controlled and regulated by a trip device or trigger 44, actuated and controlled from the forward or feeding movement of the several sheets, and adapted to be tripped by the forward edge of each sheet as the same comes into position to be engaged by the rollers 14 and 15, whereby as each sheet comes into position with its forward edge properly advanced with respect to said rollers, the trigger is tripped thereby, and the detent or latch is operated to release the spring actuated lifting means which thereupon communicates its movement to the arm 22 in order that the latter may raise the comber from the pile or stack of sheets, and terminate the forward or combing movement of the latter. As shown, the arm 22 is provided with an extension 22' arranged to be engaged by a lug 38 on the arm 101, and the arm 101 is forced in a direction to raise the arm 22 and combing roll by a spring 50 surrounding a rod pivoted to the arm 101 and interposed between a collar on the rod and a pivoted lug on the frame through which the rod slides. The arm 101 is held against the tension of the spring by a connected arm 42, the forward

end of which overlies a shoulder on the 5
detent lever 43, the lower end of which is held in position by a lug 45 on the shaft 46 which carries the trigger 44.

5 In embodying the present invention in a machine such as above described, a retarder or tail drag 61 is arranged to bear on the sheets at the rear of the combing wheel, and means is provided for automatically 10 varying the retarding action in such manner that the retarder tends to equalize the comb, or in other words the period during which the wheel must remain in action in order to advance the top sheet to the trip devices. The automatic variation of the 15 retarding action may be secured in any manner, and by any suitable mechanism which will effect an automatic equalization of the comb, the retarding action being the greatest 20 when the comb would otherwise be comparatively short, and being reduced when the comb would otherwise be comparatively long. In the preferred construction shown, the pressure of the retarder on the sheets 25 is so controlled by the sheets that the retarder is pressed on to the sheets when the comb is comparatively short, and the pressure of the retarder is relieved by removal in whole or in part when the comb becomes 30 comparatively long.

As shown, the retarder 61 comprises a press plate flexibly suspended from the lower end of a bell crank lever or angle lever comprising the two arms 62, 63 and having its 35 fulcrum at 64 upon a support 65 above the rear part of the pile or bank of sheets, in order that the press plate may engage the sheets of the pile back of the combing wheel.

Yieldable pressure is exerted upon the 40 press plate 61, and the sheets of the pile beneath the same, by means of a spring 71 arranged to abut and be pressed rearwardly against an eye 72 on the arm 63 of the bell crank lever, and thereby to swing the arm 62 45 of the lever downward into the position seen in Figs. 1 and 3. This spring is coiled around a slideable rod 73, passed through the eye 72, and pivotally connected at one end to an arm 74 of a rock shaft 75 journaled in 50 bearings upon the frame of the feeder.

The rock shaft 75 is adapted to be oscillated to slide the rod 73 back and forth endwise, and accordingly compress or release the spring 71 through the instrumentality 55 of a trifurcated lever 81, rigidly secured upon said rock shaft. Bars or links 83, 84, respectively jointed to the opposite end forks of lever 81, are extended therefrom to the forward part of the frame, past the 60 combing wheel, and are there fitted with sliding blocks 85, 86, each adapted to rest upon a pin or stud 87, 88, projecting oppositely from suitable supports provided therefor on the forward part of the frame. A 65 third rod 89 is pivotally connected at one

end to the middle fork of the lever 81, and has its other end passed through an aperture in a post 91 standing upon the frame, a spring 93 coiled around this rod 89 between the rear side of post 91 and a collar 94 on said 70 rod, serving by its tension when the lever 81 has been rocked past the perpendicular in either direction, to hold the rock shaft 75 and related parts correspondingly positioned until said lever 81 is afterward rocked in an 75 opposite direction with sufficient force to overcome the tension of said spring.

Both the bars or links 83, 84, are moved endwise through the agency of the reciprocating arm or lever 101, forming part of the spring 80 actuated means whereby the arm or lever 22 is operated, and carrying the lateral shifter plate 102, designed for contact with one or the other of said sliding blocks 85, 86. These bars or links are also capable of being 85 moved side by side, in parallel vertical planes, so as to place their respective blocks or slides in or out of the path of the shifter plate, by means of cams 103, 104 secured to a transverse shaft 105. As best seen in Fig. 90 2, the cam 103 bears at its perimeter upon a laterally directed roller 106 on the block 85, while the cam 104 contacts directly with the under side of the block 86. Whenever the spring actuated device is released by the 95 action of the sheet actuated trip device and oscillates the arm or lever 22, the shifter plate 102 is adapted to be thrown by the arm or lever 101 from its forward position shown in Figs. 1, 2 and 3, to the rearward position 100 shown in Figs. 4 and 5, in such a manner that the sheet retarding means, comprising the press plate 61 and its resilient actuating means may, if necessary, be operated.

The rotation of the cams 103 and 104 and 105 their shaft 105 is so timed relatively to the various moving parts of the mechanism that when the blocks 85, 86 stand in the reciprocal positions shown in Fig. 2, if the comb be normal, the cam 104 which controls the vertical 110 movement of the advanced block 86 will have traveled so far in the direction of the arrow 107 in Fig. 3 as to leave this block in its lowermost position, wherein it is below the path of the shifter 102, as shown in said 115 figure, before the trip device or trigger 44 shall have been tripped by the topmost sheet to release the spring actuated device and permit the same to raise the arm or lever 22 which supports the comb, and to move 120 the arm or lever 101 which carries the shifter 102 rearwardly, and the latter will therefore pass freely rearward over the lowered advanced slide block 86, and the retarding means will remain out of effective 125 operation owing to the inactivity of the slide rod 84 and other interconnecting elements.

On the other hand, if the advanced forward edges of the sheets are not spaced 130 apart to a proper and sufficient extent, it is

obvious that the topmost sheet of the pile will be withdrawn by the rollers 14 and 15, leaving the forward edge of the next underlying sheet already so close to the trip device or trigger 44 that in order to bring it into engagement with said trip device the combing wheel will have to advance such next sheet to an extent less than that which is normally required. Consequently, the 5 comb will be comparatively short, and the comber will be raised and the arm or lever 101 will be thrust rearwardly by the action of the sheet controlled trip device at a period earlier than is the case normally, and such 10 release and rearward thrust of the arm 101 occurring while the slide block 86 is elevated upon the cam 104 so as to stand in the path of the shifter 102, as represented in Fig. 5, it is manifest that the shifter will 15 then strike against the end of the advanced block 86 and force the same rearwardly to the position seen in Figs. 3 and 4, thereby rocking the lever 81 and shaft 75 in such a manner as to draw rearwardly upon the rod 20 73 and cause the plate 61 to be yieldingly pressed upon the rear ends of the sheets in the pile 11. It follows that when the comber is next again lowered into contact with the pile, its operation in feeding or combing 25 out the sheets is so retarded as to check the tendency of the sheets to advance too rapidly, and the separation between successive sheets is thus increased, and also the period during which the comber must remain in action in order to advance the top sheet into 30 position against the trip.

Rocking the lever 81 and shaft 75 in the manner just referred to also serves to advance the slide block 85 to the position illustrated in Figs. 1, 3 and 4, but the cam 103 is so timed and proportioned that if the comb continues to be comparatively short, owing to too close spacing of the forward edges of the sheets, or becomes normal, this 40 45 cam holds the advanced slide block 85 in a position sufficiently elevated to allow the shifter 102 to pass under it, when thrust rearwardly in time with the operation of the sheet controlled trip device or trigger, as 50 clearly indicated in Fig. 4, without altering the position of the retarding means or interfering with its action in any manner.

Should the comb during the retarding operation of the retarder become abnormally 55 long, however, the trip device or trigger 44 will not be tripped by the forward edge of the topmost sheet until after the cam 103 has progressed sufficiently to lower the advanced slide block 85 into the path of the shifter 60 65 102, as shown in Fig. 3, so that when the arm or lever 101 is swung or thrust rearwardly by the spring actuated means above referred to, the shifter will contact with the raised slide block 85 and force it back to the position shown in Fig. 2, whereby reverse

movement is imparted to the lever 81 and shaft 75, to relieve the pressure exerted by the retarding means on the rear part of the sheets of the pile.

It will be apparent from the above description that the retarding mechanism tends to equalize the separation between the sheets and to maintain a uniform comb throughout the operation of the machine. In operating upon those parts of the pile 75 or bank in which the sheets would otherwise comb forward easily, and in which therefore the separation between individual sheets would be slight, the retarder presses on the sheets so that the combing takes 80 place against the drag and resistance caused by the retarder. The comb and separation are therefore increased over what they otherwise would be. In operating upon those parts of the pile in which the sheets do not 85 comb forward easily, and in which the separation is comparatively great, the pressure of the retarder is relieved so that the combing takes place against a less resistance than would be the case if the retarding pressure 90 were maintained. The comb is therefore shorter and the separation less in these parts of the pile than they would be if the retarding pressure were not relieved. The retarder therefore has the greatest retarding 95 effect when the combing might otherwise be too easy or the separation too slight, and has the least retarding effect when the combing would otherwise be too hard or the separation too great.

While it is preferred to employ the construction and arrangement of parts shown and described, it will be understood that this construction and arrangement are not essential to the broader features of the invention, and may be varied and modified 100 without departing therefrom.

Having explained the nature and object of the invention, and specifically described one form of mechanism in which it may be 110 embodied, what is claimed is:—

1. The combination with sheet feeding means, of sheet-actuated trip mechanism adapted to regulate the duration of activity of said sheet feeding means, a tail drag, and 115 means automatically operated to vary the pressure of said tail drag to vary the period of activity of said sheet feeding means required to bring a sheet into predetermined position.

2. In a feeding machine, the combination of a sheet combing instrumentality, means for moving it into and out of engagement with the top sheet of a pile, sheet actuated means for determining the duration of the 125 period of activity of said sheet combing instrumentality, a tail drag, yieldable pressure exerting means for pressing the tail drag down onto the pile of sheets, and means under the control of said sheet actuated 130

means for modifying the pressure exerted by said pressure exerting means to vary the period of activity of said sheet combing instrumentality which is required to bring a sheet into predetermined position.

- 5 3. In a paper feeding machine, the combination with an automatically controlled sheet combing device capable of varying its period of activity upon a bank of sheets, 10 of sheet retarding means capable of a variable degree of pressure upon said bank of sheets, and means coöperatively actuating said sheet retarding means and sheet combing device, said actuating means being 15 adapted to reduce the pressure exerted by said sheet retarding means under a relatively long period of activity of said combing device.

4. In a feeding machine, the combination 20 of a sheet combing instrumentality, means for moving it into and out of engagement with the top sheet of a pile, sheet actuated means for determining the duration of the period of activity of said sheet combing instrumentality, a tail drag, yieldable pressure exerting means for pressing the tail drag down onto the pile of sheets, and means under the control of said sheet actuated means for modifying the pressure exerted 30 by said pressure exerting means to correspond with the period of activity of said sheet combing instrumentality; said pressure modifying means including a counter pressure bar which is movably mounted to 35 adapt it to modify the pressure exerted by said pressure exerting means and power transmitting bar which is movable into and out of position to transmit power to said counter pressure bar under the control of 40 said sheet actuated means.

5. In a paper feeding machine, the combination with an automatically controlled sheet combing device, of a tail drag operating upon the rear of a bank of sheets, and 45 variable pressure means for pressing said drag upon the bank of sheets, said variable pressure means being adapted to decrease its pressure under a relatively long period of action of said sheet combing device.

- 50 6. In a paper feeding machine, the combination of an automatically controlled sheet combing device, a tail drag operating upon the rear of a bank of sheets, and variable pressure means for pressing said tail drag to 55 the bank of sheets, said variable pressure means being adapted to change its pressure automatically to correspond with the duration of the combing period.

7. The combination with a sheet combing 60 device, of means for moving said device into and out of engagement with the top sheet of a pile, a tail drag subject to variable pressure, and means for varying the pressure of said tail drag, said means being normally 65 inoperative under a predetermined period of

activity of said sheet combing device and adapted to become operative when the period of activity changes.

8. The combination with sheet feeding means, of sheet actuated means for determining the period of activity of said feeding means required to bring a sheet into position to be delivered, a tail drag, and means for changing the pressure of said tail drag to govern the duration of said period of activity 70 of the sheet feeding means, said pressure changing means being normally inoperative under a predetermined period of activity of the sheet feeding means and adapted to be rendered operative under other than said 80 period of activity.

9. A sheet feeding machine, having, in combination, a comb, a retarder for applying pressure to the sheets during the comb, and mechanism for actuating the retarder 85 to intermittently apply such pressure to the sheets.

10. A sheet feeding machine, having, in combination, a comb, a retarder, and mechanism for actuating the retarder to apply 90 pressure to the sheets, and to render the retarder inactive when the comb exceeds a predetermined length.

11. A sheet feeding mechanism having a sheet segregating device arranged for contact upon the sheets to move the same, and a retarding device capable of movement independently of the segregating device controlled from the movement of the sheets and arranged for changeable pressure to retard 100 movement of the sheets during the action of the segregating device.

12. A sheet feeding mechanism having a sheet segregating device arranged for contact upon the sheets to move the same, a retarding device also adapted for changeable pressure upon the sheets to retard the movement thereof during the action of the segregating device, and capable of movement independently of the segregating device, 110 and means controlled from the movement of the sheets and controlling the operation of the retarding device.

13. A sheet feeding mechanism having a sheet segregating device arranged for contact upon the sheets, a retarding device also arranged for changeable pressure upon the sheets to retard the movement thereof during the action of the segregating device and capable of movement independently of the segregating device, and means controlled 115 from the movement of the sheets and arranged to control the operation of the segregating and retarding devices.

14. A sheet feeding mechanism having a 125 segregating device arranged for contact upon the sheets, a retarding device also arranged for changeable pressure upon the sheets to intermittently retard the movement thereof during the action of the segregating 130 device.

- gating device, means for actuating the segregating device, and means operated in unison with said actuating means and arranged to control the actuation of the retarding device.
15. A sheet feeding mechanism having a sheet segregating device, a device arranged for changeable pressure upon the sheets to intermittently retard the movement thereof during the action of the segregating device, means for actuating the retarding device, and means controlled from the movement of the sheets and controlling the operation of the retarding device.
16. A sheet feeding mechanism having a sheet segregating device movable in contact with the sheets to advance the same, a device arranged for changeable pressure on the sheets to intermittently retard the movement thereof during the action of the segregating device, and means actuated from the movement of the sheets and controlling said retarding device.
17. A sheet feeding mechanism having a segregating device arranged for contact with the sheets to advance the same, a device arranged for changeable pressure on the sheets to intermittently retard the movement thereof during the action of the segregating device, and means actuated from the movement of the sheets and controlling the movement of said retarding device.
18. A sheet feeding machine, having, in combination, an automatically controlled sheet combing device, a tail drag for operating on the sheets during the combing interval, and means for automatically varying the retarding action of the tail drag.

19. A sheet feeding machine, having, in combination, an automatically controlled sheet combing device, a retarder for applying pressure to the sheets during the comb, and means for relieving the pressure when the comb exceeds a predetermined length.

20. A sheet feeding machine, having, in combination, an automatically controlled sheet combing device, a retarder for applying pressure to the sheets during the comb, and means for pressing the retarder on the sheets when the comb falls below a predetermined length.

21. A sheet feeding machine, having, in combination, an automatically controlled sheet combing device, a retarder for applying pressure to the sheets during the comb, and means for pressing the retarder on the sheets when the comb falls below a predetermined length and for relieving the pressure when the comb exceeds a predetermined length.

22. In a sheet feeder, the combination, with means for operating the combing roll of a pile drag, means for presenting a supply of sheets to the combing roll, and means for relieving the pressure of the pile drag on the sheets during the combing interval.

In witness whereof I have signed my name to this specification in the presence of two subscribing witnesses.
